Filed Feb. 17, 1964, Ser. No. 78,669

Term of patent 3½ years

(Cl. D52—2)

FIG. 4

FIG. 1 is a view in perspective showing the front and one side of a measuring dispenser for coffee or the like embodying our new design;

FIG. 2 is a view in perspective of the bottom and reverse side thereof;

FIG. 3 is a view in elevation of the dispenser showing in phantom both a container to which the dispenser is attached and a vessel into which the material is dispensed.

FIG. 4 is a top plan view thereof.

The fragmentary broken line portions in FIG. 3 are depicted for illustrative purposes only.

We claim:

The ornamental design for a measuring dispenser for coffee or the like, substantially as shown and described.
